UNITED STATES PATENT OFFICE.

FRITZ DÜHRKOP, OF NEW YORK, N. Y.

BAKER'S OVEN.

SPECIFICATION forming part of Letters Patent No. 379,941, dated March 27, 1888.

Application filed August 6, 1887. Serial No. 246,252. (No model.)

To all whom it may concern:

Be it known that I, FRITZ DÜHRKOP, of the city of New York, county and State of New York, have invented a new and improved 5 Baker's Oven, of which the following is a specification.

This invention relates to various improvements in a baker's oven, and more particularly to an arrangement of flues, whereby a uniform 10 heat is imparted to the top and bottom of the oven.

The invention also relates to several details of construction.

It consists in the various features of improvement, more fully pointed out in the claims.

In the accompanying drawings, Figure 1 is a vertical transverse section on line *u u*, Fig. 2. Fig. 2 is a vertical longitudinal section on line *v v*, Fig. 1. Fig. 3 is a horizontal section 20 on line *w w*, Fig. 1. Fig. 4 is a horizontal section on line *x x*, Fig. 1. Fig. 5 is a horizontal section on line *y y*, Fig. 1. Fig. 6 is a detail front view of the oven-door; Fig. 7, a vertical section on line *z z*, Fig. 6; and Fig. 8, 25 a detail back view of part of the roof of the baking-chamber.

The letter *a* represents the fire-place of a baker's oven, opening toward the rear of the same. From the grate the heat and products 30 of combustion pass first forward and around a fire-wall, *b*, thence backward through the upper part, *a'*, of the fire-place, and thence around a fire-wall, *c*, into a number of parallel flues, *d d*, Fig. 3, extending directly beneath 35 the bottom *e* of the baking-chamber. This bottom is composed of two walls of fire-brick inclosing a bed of sand. From the flues *d* the products of combustion enter a transverse passage, *d'*, that leads them to two upright flues, *f*, located at the right and left of the baking-chamber *g*, Figs. 1 and 4. From the 40 upright flues *f* the products of combustion pass above the baking-chamber *g* and between two arched roofs, *g' h*, divided by a heating-space. This heating-space has a central partition, *i*, two lateral inclined partitions, *j*, and 45 two short deflecting-walls, *k*, Fig. 5.

The products of combustion emerging from flues *f* are deflected by walls *k* against inclined 50 partitions *j*, around which they flow, to finally pass forward between such partitions and the central partition, *i*, and out into the smoke-stack

l. By this construction both the bottom and the top of the baking-chamber are thoroughly and properly heated. The fire chamber *a* is also 55 directly connected to the heating-space between the arched roofs *g' h* by means of direct upright flues *m*, Figs. 1 and 2, by means of which the heat may, if desired, be directly conducted to the top of the baking-chamber. 60 These flues *m* are provided with suitable dampers.

n is a vent connecting the baking-chamber with the smoke-stack and permitting the discharge of the gases. 65

I attach importance to the mode of constructing the heating-space above the oven—that is to say, to the use of the two inclined partitions *j* in connection with the deflectors *k*. I have found that by this construction the 70 heat is thrown against the partitions, and, running along their inclined faces, a uniform heating of the oven is produced without any cool or comparatively cool spaces.

In Figs. 6 and 7, *o* is the door of the baking-chamber *g*, that turns inward on pivot-pin *p*, which is extended at one end beyond its bearing. This extension carries a balance-weight, *q*, and has a notched end, by which it grasps a gas-cock, *r*, in a pipe, *s*, the burner of which 80 is placed opposite a mica window in the baking-chamber. This burner is never entirely extinguished. When the door is opened, the balance-weight will maintain it at any desired inclination, and at the same time the flame 85 from the burner will be turned up as long as the door is maintained by the weight in its open position. When the door is closed, the flame will be automatically turned down.

Fig. 8 shows the mode in which the roof *g'* is anchored. The series of fire-bricks *g'* composing this roof are flanked at each edge by an angle-iron, *g*, having a hook-shaped projection, *g*', that holds a plate, *g*'', bearing against the faces of the fire-bricks and preventing their longitudinal displacement. *g*'' is one of a set of upright metal plates placed against the edge of angle-iron *g*'. The plates *g*'' at opposite sides of the roof are connected by means of bolts and nuts, and thus the entire roof is properly strengthened.

I claim as my invention—

1. The combination, in a baker's oven, of fire-place *a* and chamber *g*, with upright flues

f, and double-roof *g' h*, having inclined partitions *j* and deflectors *k*, substantially as specified.

2. The combination, in a baker's oven, of 5 fire place *a*, with the parallel flues *d* and transverse flue *d'* beneath the baking-chamber *g*, and with the upright flues *f* at the sides thereof, and with a double roof having central partition, *i*, inclined partitions *j*, and deflectors *k*, 10 substantially as specified.

3. The combination, in a baker's oven, of fire-place *a*, having fire-walls *b c*, with the flues *d*, transverse flue *d'*, upright flues *f m*, double roof *g' h*, partitions *i j*, deflectors *k*, 15 vent *n*, and smoke-stack *l*, substantially as specified.

4. The combination of oven-door *o*, having

pivot-pin *p*, which is extended at one end beyond its bearing and has a notched end, with balance-weight *q*, carried by such extended 20 pivot, and with gas-pipe *s* and cock *r*, that is engaged by such notched end, substantially as specified.

5. The combination, in a baker's oven, of fire-bricks *g²*, with the angle-irons *g³*, having 25 hook-shaped projections *g⁴*, and with the plates *g⁵ g⁶*, the whole constituting the arched roof of the baking-chamber, substantially as specified.

F. DÜHRKOP.
